UNITED STATES PATENT OFFICE.

THOMAS HENRY BELLOWS, OF WALLA WALLA, WASHINGTON.

CAR-REPLACER.

1,391,819.

Specification of Letters Patent. Patented Sept. 27, 1921.

Application filed February 5, 1921. Serial No. 442,792.

To all whom it may concern:

Be it known that I, THOMAS HENRY BELLOWS, a citizen of the United States, residing at Walla Walla, in the county of Walla 5 Walla and State of Washington, have invented a new and useful Car-Replacer, of which the following is a specification.

This invention relates to car replacers, and more particularly to a reversible replacer, or one which may be employed for 10 replacing cars regardless of the direction of movement of the car to replace the same.

The primary object of the invention is to provide a novel connection between the 15 body portion and track section of the replacer, whereby movement of one element with relation to the other, during the replacing operation, is absolutely prevented.

A further object of the invention is to 20 provide a connection of this character which will permit of the quick and easy adjustment of one element with respect to the other in reversing the replacer.

With the foregoing and other objects in 25 view which will appear as the description proceeds, the invention resides in the combination and arrangement of parts and in the details of construction hereinafter described and claimed, it being understood that 30 changes in the precise embodiment of the invention herein disclosed, may be made within the scope of what is claimed, without departing from the spirit of the invention.

35 Referring to the drawing:—

Figure 1 is a side elevational view partly broken away, of a car replacer constructed in accordance with the present invention.

Fig. 2 is a plan view of the same.

40 Fig. 3 is a sectional view taken on line 3—3 of Fig. 1.

Fig. 4 is a sectional view taken on line 4—4 of Fig. 1.

Referring to the drawing in detail, the 45 main section or body portion of the replacer is designated by the reference character 5, the body portion being provided with the usual replacing groove 6, which merges with the camming surface 7, that is disposed 50 adjacent to the rail, in the operating of the device for camming the wheels of the car being replaced, to the rail of the track.

Each end of the section 5 is provided with a cut out portion providing the arms 8, which 55 in turn are provided with cut out portions 9 disposed intermediate the upper and lower

edges of the arms 8, which cut out portions are designed to accommodate the flanges 10 provided on the tongue 11 of the rail section of the replacer, and which extend 60 laterally therefrom.

These arms 8 are provided with openings 12, which openings register with a suitable opening provided in the tongue 11 of the rail section 13 whereby a bolt or other securing means may be passed through the 65 registering opening to secure the sections together.

In order that the replacer will be held against lateral movement, the usual spurs 70 14 are provided, which spurs embed themselves in the tie supporting the rail of the track. From the foregoing it will be obvious that if it is desired to use the replacer for replacing a car in a direction opposite to 75 that in which the track section is positioned, it is only necessary to remove the securing pin, and reverse the track section 13. Due to the construction as shown, movement of one section of the replacer with respect to 80 the other is absolutely prevented.

It might be further stated that a shoulder 15 is formed between the arms 8 at the ends of the body portion, which shoulders accommodate the extension 16 formed on one 85 end of the tongue 11 of the track section, thereby eliminating any possibility of a vertical movement of the track section with respect to the body portion under the weight of a car passing thereover. 90

Having thus described the invention, what is claimed as new is:—

1. In a car replacer, a body portion, said body portion having a cut out portion at either end thereof providing arms, a track 95 section having a tongue, said tongue adapted to be disposed between the arms of the body portion at either end thereof, each of said arms having a notch formed therein, means carried by the track section and adapted to be positioned within the notches of the arms for restricting movement of the track sections with respect to the body portion, and means passing through the body and track sections for securing the body portion and track section against movement. 100

2. In a car replacer, a body portion, a track section, said body portion having cut out portions formed at the ends thereof, providing arms, a track section, said track section having a tongue adapted to be po 110

- sitioned between the arms of the body portion, each of said arms having a cut out portion, means carried by the track section and adapted to be positioned in the cut out portions of the arms, for restricting movement of the track section with respect to the body portion, and means passing through the arms and tongue for securing the track section and body portion together.
- 10 3. In a car replacer, a body portion, said body portion having cut out portions formed at the respective ends thereof, said cut out portions forming spaced arms, a shoulder formed between the arms, a tongue carried by the track section and having an extension, said extension adapted to be supported by the shoulder, and means passing through the tongue and arms for securing the track section and body portion together.
- 15 4. In a car replacer, a body portion hav-

ing cut out portions formed at the ends, the cut out portions providing arms, a track section having a tongue positioned between the arms, a shoulder formed between the arms, said tongue having an extension 25 adapted to rest on the shoulder, each of said arms having a cut out portion, flanges carried by the track section and fitted in the cut out portions of the arms for restricting movement of the track section with relation to the body portion, and a bolt passing through the arms and tongue for securing the body portion together.

In testimony that I claim the foregoing as my own, I have hereto affixed my signature 30 35 in the presence of two witnesses.

THOMAS HENRY BELLOWS.

Witnesses:

EARL W. BENSON,
LEVINA C. FLEMING.
